UNITED STATES PATENT OFFICE.

LESTER R. WELLMAN, OF CHICAGO, ILLINOIS, ASSIGNOR TO FRIEDELEY-VOSHARDT CO.,
OF CHICAGO, ILLINOIS, A CORPORATION OF ILLINOIS.

DESIGN FOR A PLATE FOR LIGHTING-FIXTURES.

51,404.

Specification for Design.

Patented Oct. 16, 1917.

Application filed August 24, 1917. Serial No. 188,079. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Plate for Lighting-Fixtures, of which the following is the specification, reference being had to the accompanying drawing, forming part thereof.

Figure 1 is a side view of a plate for lighting fixtures, showing my new design.

Fig. 2 is a front view of the same.

I claim:

The ornamental design for a plate for lighting fixtures, as shown.

LESTER R. WELLMAN.
